UNITED STATES PATENT OFFICE.

EZECHIEL WEINTRAUB, OF SCHENECTADY, NEW YORK, ASSIGNOR TO GENERAL ELECTRIC COMPANY, A CORPORATION OF NEW YORK.

ELECTRICAL ILLUMINATION.

1,074,303.

Specification of Letters Patent. Patented Sept. 30, 1913.

Application filed February 9, 1907. Serial No. 356,541.

To all whom it may concern:

Be it known that I, EZECHIEL WEINTRAUB, a citizen of the United States, residing at Schenectady, county of Schenectady, 5 State of New York, have invented certain new and useful Improvements in Electrical Illumination, of which the following is a specification.

My present invention relates to the production of light.

It comprises a new method of transforming electrical energy into light by heating a refractory body to incandescence through the medium of electrical energy passed 15 through an attenuated vaporous medium.

It also comprises means whereby this result may be attained.

In accordance with the provisions of the statutes relating to patents, I have herein- 20 after described how my invention may be applied in practice, and I have illustrated one form of apparatus suitable for use in accordance with my invention. I do not, however, consider that my invention is limited to this particular form of apparatus, and in the claims appended hereto I have 25 defined the scope of my invention as I understand it.

Before considering in detail the fundamental principles underlying my invention, reference is made to the accompanying drawings showing two forms of apparatus whereby my invention may be applied to the useful arts.

35 Figure 1 shows in section a vapor-electric device provided with a capillary tube according to my invention; Fig. 2 is a fragmentary view of a modified device in which the refractory tube is insulated from both 40 electrodes.

Fig. 1 illustrates an evacuated envelop 1 of glass or other suitable material somewhat similar in form and proportions to the envelops used with mercury vapor apparatus. 45 The envelop has a relatively large bulb or condensing chamber 2 at the top, and into this projects a leading-in conductor 3 through which electrical energy may be introduced into the envelop. An electrode 4 of graphite or other suitable material is connected to the lead-wire 3 and coöperates with other elements in a manner hereinafter described. The envelop is provided with a second electrode 5 connected with a second

leading-in conductor 6 by which connection 55 may be made with the electrical circuit. In the drawing I have shown electrode 5 as consisting of mercury, but other material may be used, and in fact, under certain conditions, certain other materials have 60 marked advantages, as hereinafter set forth. The external circuits of the device may consist of a conductor 7 connecting electrode 4 with one side of an electrical circuit, say the positive side of a direct current source, 65 and a similar conductor 8 for the other electrode of the device. A switch 9 and resistance 10 are connected in parallel with the device for use during the starting operation. A reactance 11 may be connected in 70 series with the conductor 7, and a resistance 12 may be connected in series with conductor 8.

The various elements above described would constitute what might be termed, a 75 mercury arc lamp, of which electrode 4 is the anode and electrode 5 the cathode. Such a lamp could be started on a direct current source by closing switch 9 to cause a current to flow in reactance 11, and then 80 opening the circuit at switch 9 to allow reactance 11 to discharge at high potential across the gap between electrodes 4 and 5. Such a high potential discharge would serve to establish a conductive condition between these electrodes and direct current would pass with relative freedom. My present invention, however, contemplates the use of an additional element; this element is illustrated in the drawing as a tube 13 of 85 constricted diameter extending from the neighborhood of electrode 4 to the neighborhood of electrode 5. This tube is provided at the top with an enlargement 14 surrounding the electrode 4 and leaving a 90 small annular space about the electrode. The top of the tube is contracted to form a close joint with the refractory bushing 15 which separates electrode 4 from the glass which incloses the leading-in conductor 3. 100 The joint between the bushing 15 and the constricted neck need not be vapor tight. The lower end of the tube 13 is flared outward to form a cup 16 at the surface of the mercury electrode. Suitable stays or 105 supports 17 fitted with refractory bushings 18 may be used to hold tube 13 in position. I have not specified the material of the

tube as I contemplate the use of various materials differing radically in some of their properties.

Assuming, for purposes of illustration, that the element 13 is a porcelain tube with a bore ranging in diameter from $1/4$ inch down to $1/64$ inch or even less, the operation of the device is as follows:—An electromotive force of several hundred volts is impressed across conductors 7 and 8, but no current flows between anodes 4 and 5 because of the non-conductive space which separates them. Switch 9 is then closed to store energy in reactance 11; it is subsequently opened to cause that reactance to discharge its energy at high potential between electrodes 4 and 5. This discharge will take place through the bore of the porcelain tube to the small electrode surface exposed within the cup 16 at the lower end of the tube. This discharge of energy serves to establish a conductive path between electrodes 4 and 5, and through this path a direct current is maintained by the voltage impressed on conductors 7 and 8. Under the conditions above set forth the current is in reality carried by a mercury arc inclosed by the porcelain tube 13. If the tube has a small bore, the arc will be of a very small cross-section and of relatively high voltage. The current may be small, say in the neighborhood of a fraction of an ampere. I find that if I continue to supply current to the arc between the electrodes I can gradually heat up the porcelain tube to any desired temperature, even up to that at which the tube melts and goes to pieces.

From the above description it will be understood that the inclosed tube 13 may be raised to incandescence even though it is initially non-conductive, solely by the heating action of current passed through the vaporous or gaseous medium in proximity to the material to be heated.

I have above referred to a porcelain tube as it is one of the materials easy to form into a tube of small bore, and is a material the properties of which are relatively well understood. Porcelain, however, is not the best material available when the device is to be used as a source of illumination. Porcelain melts down at about 1400° centigrade. Tube 13 instead of being of porcelain, may be made of silica. As silica is transparent, the light delivered by the device is in this case a blended light containing rays from the incandescent silica and other rays from the mercury arc within the tube.

The evacuated space outside the heated tube serves to prevent, in large measure, the dissipation of heat by conduction, so much so that I have succeeded in heating silica tubes to melting temperature with a current as small as one-half an ampere and an electromotive force of about 100 volts. The silica tube in this case was approximately

five inches long and had a bore of about $1/25$ of an inch.

For improving the radiation capacity and securing the benefit of other advantageous properties, I may use a tube of refractory oxid such as thorium oxid or zirconium oxid. Thorium oxid is well adapted for this use because of its stability at high temperatures. A thorium body has the further advantage that it possesses selective radiation. When the thorium oxid tube is used as shown in Fig. 1, the oxid is brought to incandescence by energy liberated by the mercury arc; not by energy developed in the thorium oxid itself by the passage of current therethrough. I aim to keep all the electrical energy passing through the arc, so that no electrolysis or other disintegrating action may take place in the thorium oxid. The thorium oxid is preferably as pure as possible and free from other rare earth oxides which might tend to increase the conductivity and impair the refractory properties. In an apparatus of the type illustrated in the drawing, several factors tend to prevent the passage of current through the thorium oxid. The mercury or other vaporizable material of electrode 5 furnishes an efficient source for the liberation of vapor, and receives energy from the arc with a comparatively small voltage drop at the electrode surface. There is therefore little tendency for the arc to desert the metal and run to the oxid tube as cathode. Pure thorium oxid has a very high electrical resistance and even up to red heat, say 1400° centigrade, does not conduct appreciably. The resistance of the mercury arc decreases somewhat as its temperature increases, thus tending to prevent the passage of current through the oxid.

I have pointed out the fact that the conductivity of the refractory tube is not relied on to maintain incandescence, but I do not consider that I am limited to the use of non-conductive material for refractory tubes. I understand my invention to include refractory tubes of such material as boron, tungsten, and other high melting elements refractory enough to stand the high temperature and chemically inert with respect to the mercury or other vaporizable material used as cathode in the apparatus. In such cases, however, I consider it advisable to insulate or separate the refractory tube from one or both of the electrodes.

A modified form of device is illustrated by Fig. 2, in which the tube 13 is insulated from the electrode by the refractory insulating bushing 19, and from the mercury electrode 5 by being out of contact with the latter, as clearly shown.

I have mentioned the fact that the evacuated space surrounding the refractory tube prevents radiation of heat from the tube.

The constant vaporization of mercury tends, however, to increase this radiation. The heat insulation can be made more effective by the use of a cathode of amalgam or of 5 zinc or some metal which does not vaporize as easily as mercury.

What I claim as new and desire to secure by Letters Patent of the United States, is:

1. The process of electric lighting which 10 consists in passing a mercury vapor arc through a tube of very small bore consisting of refractory material in an exhausted space, and delivering sufficient energy to said arc to maintain the walls of said tube at incandescence.

2. The method of maintaining a fine bore tube of refractory material, excessive in 20 length with respect to its diameter, at incandescence which consists in passing a metallic vapor arc through its bore in an exhausted space, whereby a luminant of low current and high voltage characteristics is secured.

3. The process of converting electrical energy into light which consists in striking a 25 high voltage, low current metallic vapor arc through an evacuated space in a fine bore tube of refractory material excessive in length with respect to its diameter, whereby said material is heated to incandescence.

4. The combination of a mercury electrode, a coöperating electrode, a highly refractory tube of very fine bore interposed between said electrodes, an evacuated inclosing envelop and means for striking an arc between said electrodes through the bore 35 of said tube, thereby maintaining it at incandescence.

5. The combination of an exhausted envelop, electrodes therein, at least one of which consists of mercury, and a tube of 40 highly refractory material having a diameter of about 1/4 to 1/64 of an inch, and means for striking an arc through the bore of said tube thereby maintaining it at steady 45 incandescence.

6. The combination of an exhausted envelop, electrodes therein, at least one of which consists of mercury, a tube of very small bore consisting of thorium oxid, and means for starting an arc between said electrodes through said tube to heat the same to 50 incandescence.

In witness whereof, I have hereunto set my hand this 7th day of February, 1907.

EZECHIEL WEINTRAUB.
